(57) **CLAIM**

The ornamental design for a holder for toothpick, as shown and described.

DESCRIPTION

FIG. 1 is a front, right side perspective view of a first embodiment of a holder for toothpick, showing my new design;

FIG. 2 is a rear, left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, right side perspective view of a second embodiment of the holder for toothpick;

FIG. 10 is a rear, left side perspective view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof;

FIG. 16 is a bottom plan view thereof;

FIG. 17 is a front, right side perspective view of a third embodiment of the holder for toothpick;

FIG. 18 is a rear, left side perspective view thereof;

FIG. 19 is a front elevation view thereof;

FIG. 20 is a rear elevation view thereof;

FIG. 21 is a left side elevation view thereof;

FIG. 22 is a right side elevation view thereof;

FIG. 23 is a top plan view thereof; and,

FIG. 24 is a bottom plan view thereof.

The broken lines in the figures illustrate portions of the holder for toothpick that form no part of the claimed design.
